Des. 240,400
Patented July 6, 1976

240,400

PACKAGING CONTAINER FOR ELECTRONIC THERMOMETER PROBES

Michael J. Marino, Lynn, Mass., assignor to
ROI Corporation, Peabody, Mass.

Filed Dec. 13, 1973, Ser. No. 424,361

Term of patent 14 years

Int. Cl. D9—03

U.S. Cl. D9—193

FIG. 1

FIG. 2

FIG. 5

FIG. 1 is a top-plan view of a packaging container for electronic thermometer probes showing my new design;

FIG. 2 is an elevational view thereof taken along the longest edge of FIG. 1;

FIG. 3 is an elevational view thereof taken along the shortest edge of FIG. 1;

FIG. 4 is a view of the package when folded along the vertical center line as illustrated in FIG. 1, and looking from the left end thereof;

FIG. 5 is a bottom-plan view thereof.

I claim:

The ornamental design for a packaging container for electronic thermometer probes, as shown.
